CLASP FOR BRACELETS

Saul Ritter, New York, N. Y., assignor of one-half
to Marvin J. Bruner, New York, N. Y.

Application November 3, 1948, Serial No. 58,078

2 Claims. (Cl. 24—71)

1

This invention relates to an improvement in clasps or connectors for watch bracelets of the extension type comprising elements which fold and unfold to close and open the clasp.

An object of the invention is to provide a device of this character wherein the foldable members when in closed relation will be held against separation by means operating automatically when the members are moved to folded positions.

Another object of the invention is to provide for positively locking the members in folded relation by means so arranged as to provide a simple and convenient means for releasing the members.

Another object of the invention is to provide a locking means operable to cause the members when in folded relation to cooperate with pawl and ratchet means for holding an extension member in an adjusted position and for releasing the said extension member when the foldable members are unfolded.

Another object of the invention is to provide one of the foldable members with an elongated tension latch element or finger mounted in one of the members to automatically lock the members when folded and manually operable for releasing of said members.

Other objects and advantages of the invention will be evident from the following description together with the accompanying drawing, in which:

Fig. 1 is a side elevational view of a clasp or connector constructed in accordance with the present invention and shown connected to the ends of a bracelet chain.

Fig. 2 is a top plan view of the clasp shown in Fig. 1;

Fig. 3 is a perspective view of the clasp shown with the members partly unfolded;

Fig. 4 is a longitudinal cross-sectional view of the clasp with the members in folded relation;

Fig. 5 is a view taken on line V—V in Fig. 4;

Fig. 6 is a view taken on line VI—VI in Fig. 4;

Fig. 7 is a transverse cross-sectional view of the clasp partly open, and

Fig. 8 is a longitudinal cross-sectional view of the clasp taken on line VIII—VIII in Fig. 4.

In accordance with the present invention a connector or clasp may comprise a plurality of foldable members hingedly connected so as to fold and unfold to close and open the clasp. This general type of clasp has been used in many forms and has been considered satisfactory from the standpoint of providing a convenient means of enlarging or extending the length of a bracelet to fit over the hand and in providing the neces-

sary contraction to firmly hold the bracelet on the wrist and especially when the bracelet is used as a wrist watch band or strap.

Numerous structures have been proposed for holding the members of a clasp or connector in retained relation when folded. A common form of such holding means has been the provision of lugs or detents which frictionally engage when the members are in closed or folded position. 5

10 Frictional contact for retaining the members, although initially satisfactory is subject to the disadvantage of wear so that in time, during use, the parts no longer hold to effectively keep the members from unfolding.

15 It has also been proposed to use means for positively locking the members in folded relation. This has been accomplished in numerous ways as by employing a slide or other member to lock the parts in folded relation, the disadvantage being in providing a simple, visible and conveniently actuated means for unlocking the members.

20 In a device of the present character which is in the nature of a piece of jewelry it is necessary to not only provide an effective mechanical arrangement of parts but this object must be accomplished without departing from the required ornamental or pleasing appearance of the device.

25 Furthermore, it has been found that a device 30 of this type must be provided with a locking means requiring no special effort or skill to release or unlock on the part of the user. By reason of the present novel arrangement of the latching or retaining means in combination with the foldable parts of the clasp a simple and effective lock and release is provided having the desired ornamental effect and so constructed as to be quickly and conveniently releasable; at the same time maintaining a desirable over-all appearance.

35 As illustrated a preferred embodiment of the invention may comprise three foldable members consisting of a cover member 11, intermediate member 12 and a bottom member 13. As shown more clearly in Fig. 7 the member 11 is of trough shape comprising a top wall 14 and side walls 15 and 15' having inturned flanges 20 and 20' respectively to provide a guide or track 22'. The intermediate member 12 is connected by hinge 16 at one end 16 to the side walls 15 and 15'. 40 As shown the hinged end 16 is disposed in spaced relation or off-set to an end 17 of the cover member 11 for purposes to be presently described.

45 The other end 18 of the intermediate member 12 is hinged at 19 to an end of the bottom mem-

ber 13. When the clasp is contracted and the foldable members positioned in over-lapping contacting relation as shown in Fig. 4 they are retained in fixed relation by a latch member 21 mounted in the cover member 11 and engageable with a ward or detent 22 on the bottom member 13. The latch member 21 is integral with one end of a spring arm or finger 23, the opposite end of the arm being fastened at 24 to end 25 of the cover member 11.

As shown in Fig. 6 the latch 21 on the spring arm or tension member 23, when in its normal position, engages the ward 22. By reason of its resiliency the spring arm 23 carrying the latch 21 automatically causes the arm to move laterally permitting the latch to snap over the detent 22 when the foldable members are pressed into folded relation. For the purpose of releasing the latch, the spring arm 23 is provided with a finger piece 26. When the finger piece is pressed inwardly the spring arm 23 is moved to disengage the ward 22 and release the members. The releasing mechanism as shown is disposed at one end of the members when folded. Furthermore, it will be evident that by reason of the position of the releasing means the natural action performed is to compress the finger piece and at the same time lift it to unfold the members.

The position of the releasing means therefore facilitates the opening or unfolding of the folded members thus facilitating and simplifying the operation of expanding the clasp. The location of the releasing means at one end of the cover member is accomplished as shown by hingedly connecting the end 16 of the intermediate member at a point on the cover member removed from end 17 thereof. This makes possible the disposition of the finger piece 26 and latch 21 between the end 16 of the intermediate member and the adjacent end 17 of the cover member 11. As shown more clearly in Figs. 4, 7 and 8 the top wall of the cover member is extended and bent to form end 17 into a tubular housing or guide for the finger piece 26. Thus the finger piece 26 is located at the end of the cover member 11. Therefore when the finger piece is moved endwise in opposition to spring 23 to actuate the latch and release the folded members, the location of the finger piece at the extreme end of the cover member, makes it possible to obtain the full benefit of the lever action with hinge 19 as the fulcrum. The bottom member 13 is also of trough shape and is provided with side walls 27 and 27' each of said walls being provided with a notch 28 to permit the walls 27 and 27' to clear the hinge 16 connecting the cover and the intermediate member. The member 13 is of such dimension as to be received between inturned ends 20 and 20' so that when the foldable members are in folded relation the cover member 11 and the bottom member 13 form a substantially smooth outside surface of the members when closed.

In clasps of the present type it is desirable to provide means for adjusting the bracelet after the foldable members have been contracted. For this purpose it has been the practice to provide a slidable member which may be adjusted and held in an adjusted position. In the present construction a member 29 is provided mounted in the cover member and slidably in a track formed of the walls 15 and 15' and the inturned flanges 20 and 20'. As shown the slidable member 29 is provided at one end thereof with a pawl 31, the opposite end of the member being attachable to an end of a bracelet or band such as a wrist watch

strap 32. The other end of the strap 32 being attachable at 33 to an end of the bottom foldable member 13. For the purpose of holding the slideable member 29 in adjusted position the intermediate member 12 is provided with a series of teeth 33. When the foldable members are in closed position, as shown in Fig. 4 the pawl 31 engages with the teeth 33 holding the slideable member in a selected adjusted position against outward movement.

From the foregoing it will be evident that by reason of the present automatic locking relation between the lower foldable member 13 with the cover member 11, the members when in closed folded relation maintain the pawl 31 in contact with the teeth 33. On the other hand immediately upon actuation of the finger piece 26 the members are released and opened as shown in Fig. 7 automatically releasing the pawl 31 from the teeth 33 and permitting the extension member to slide to its extreme outward position. The clasp therefore immediately expands to its full extent permitting the removal of the bracelet over the hand.

When the clasp is used as a connector for a wrist watch bracelet, for example, it may be readily opened to its fullest extent permitting the free passage of the hand to position the bracelet upon the wrist. The foldable members may then be contracted to their folded relation whereupon the latch 21 automatically engages the detent or lug 22 to hold the parts against separation and closed relation of the members 11 and 13 maintains the pawl 31 engaged with teeth 33. If desirable the bottom member 13 may be provided with raised portions 34 and 34' to frictionally engage the edges of flanges 20 and 20' to hold the end 25 of the cover and end 19' of the bottom member in firm relation. Inasmuch as the foldable members are positively locked the duty imposed on the friction means is negligible. When the bracelet is applied to the wrist and the foldable members closed as above explained the slideable member may then be moved inwardly to cause its pawl 31 to engage teeth 33, the operative relation between the pawl and teeth being effected by reason of the latching means which firmly holds the members in fixed relation. The bracelet may therefore be adjusted by moving the slideable member inwardly until the bracelet fits the wrist to the satisfaction of the user.

As above set forth a slight pressure on the finger piece 26 immediately releases the foldable members as well as the slideable member permitting a free and convenient removal of the bracelet.

The present invention therefore provides a simple and effective clasp or connector which may be quickly and conveniently contracted to lock the members against unfolding and at the same time putting the slideable member into operative condition.

Although a preferred embodiment of the invention is shown and described herein, it is to be understood that modifications may be made therein without departing from the spirit and scope of the invention as set forth in the appended claims.

I claim:

1. A clasp comprising a cover member having a top wall and side walls, an intermediate member, a hinge connecting one end of said intermediate member to said side walls, said hinge being positioned in adjacent spaced relation to one end of said cover member, said end of the cover member having the top wall extended to provide

a tubular housing open at one end, a latch member mounted in said cover member and positioned between said hinge and said housing, a spring member for normally urging said latch member in a direction transverse to the longitudinal axis of said cover member, a bottom member having one end hingedly connected to the other end of said intermediate member, a detent in adjacent spaced relation to the other end of said bottom member for engaging said spring actuated latch member when the cover, intermediate and bottom members are in folded relation, a movable member disposed in and extending from the open end of said housing to provide a finger piece for actuating said latch member to permit the folded members to be unfolded.

2. A clasp comprising a cover member having a top wall and side walls, an intermediate member, a hinge connecting one end of said intermediate member to said side walls, said hinge being positioned in adjacent spaced relation to one end of said cover member, said end of the cover member having the top wall extended to provide a tubular guide member, a latch member mounted in said cover member and positioned between said hinge and said guide member, a spring mem-

ber for normally urging said latch member in a direction transverse to the longitudinal axis of said cover member, a bottom member having one end hingedly connected to the other end of said intermediate member, a detent in adjacent spaced relation to the other end of said bottom member for engaging said spring actuated latch member when the cover, intermediate and bottom members are in folded relation, a finger piece disposed in said guide member for transverse movement to disengage said latch member to permit said folded members to be unfolded.
